UNITED STATES PATENT OFFICE.

AUGUST H. PAPE, OF KENTFIELD, CALIFORNIA.

AUTOMOBILE SIDE CURTAIN.

Application filed May 17, 1921. Serial No. 470,252.

To all whom it may concern:

Be it known that I, AUGUST H. PAPE, a citizen of the United States, residing at Kentfield, in the county of Marin and State 5 of California, have invented new and useful Improvements in Automobile Side Curtains, of which the following is a specification.

The present invention relates to improvements in automobile top and body construction and has special reference to certain improvements in side curtains, by the use of which, a touring car may be quickly and easily converted into a closed car.

The primary object of the invention is to 15 provide side curtain construction, which, by reason of its arrangement, mounting and means of operation will be superior to the ordinary side curtains in point of simplicity, cheapness of construction, ease and facility 20 of attachment, ease of operation, neatness of appearance and the provision for an easy assembling and disassembling of the curtain whereby repair and renewal of parts thereof will be facilitated.

25 Another object is to provide side curtain construction of the character described which may be installed without necessitating any material change in the construction of the automobile top and body and which will 30 not be subject to being blown out of place or otherwise deranged by the wind.

Another object is to provide side curtains of the character described which will be flexible and attached to the top so as to roll 35 or move into concealed position at a point beneath the top and when unrolled and extended will close the sides of the automobile, there being novel means for guiding the curtains into closed and concealed position 40 which means will prevent bulging or blowing out of the curtains when extended.

A further object is to provide novel means for slidably securing the side edges of the curtains to guide means supported by the top, 45 said securing means serving to rigidly and firmly hold the edges in place whereby the curtains will be taut and not likely to bulge or become deranged.

50 A further object is to provide side curtains of the character described which will be made in two parts detachably secured together, whereby the part not exposed, when the curtain is extended, may be of cheaper quality and the assembling and disassembling of the curtain may be more easily and readily effected.

The invention possesses other advantages and features some of which, with the foregoing will be set forth at length in the following description where I shall outline in 60 full that form of the invention which I have selected for illustration in the drawings accompanying and forming a part of the present specification. In said drawings I have shown one form of the construction of my 65 invention, but it is to be understood that I do not limit myself to such form since the invention as expressed in the claim may be embodied in a plurality of forms.

Referring to the drawing:

70 Figure 1 is a fragmentary side elevation of an automobile showing the side curtains in closed position.

Figure 2 is a fragmentary longitudinal sectional view of the top showing one curtain in closed or down position, the other curtain being removed.

Figure 3 is a broken horizontal sectional view of the upright guide members which extend between the body and top on the 80 sides of the body.

Figure 4 is a fragmentary cross sectional view of a part of the top showing the curtain extended or drawn down.

Figure 5 is a sectional view taken on line 85 5—5 of Fig. 4.

Figure 6 is a fragmentary detail sectional view of a curtain showing the manner of slidably connecting the side edges thereof 90 with the guide members.

Figure 7 is a fragmentary side elevation shown partly in section, of a curtain and means for slidably securing the same to the guides.

Figure 8 is an enlarged fragmentary vertical sectional view of a guide member and slide member therein.

Figure 9 is a cross section of a part of the top showing a modified form of curtain in down position.

Figure 10 is a sectional view taken on line 10—10 of Fig. 9 showing one curtain raised and the other lowered.

Figure 11 is a fragmentary enlarged top plan view of the modified form of curtain 105 shown in Figs. 9 and 10.

Figure 12 is a fragmentary end or edge elevation of the form of curtains shown in Fig. 11.

Referring first to the embodiment of the 110 invention shown in Figs. 1 to 8 inclusive, there is provided on each side of the auto-

mobile top, 1, a pair of side curtains, 2. The curtains of each pair are arranged to slide bodily from extended or closed position to up or concealed position under the top and 5 may be independently operated. To provide for this the curtains slide between two closely arranged but spaced sheets 3 and 4 of thin metal or other suitable material there being a pair of such sheets on each side of 10 the longitudinal center member, 5, of the top.

These sheets extend from the forepart of the top to a point at which the fixed side portions 6 of top commence, on each side of 15 the top, and their longitudinal edges are disposed in line with the longitudinal center line and lower edge of the overhang portion 7 of the top respectively, whereby a pocket or compartment large enough to receive the 20 two curtains is provided. The sheets 3 and 4 are secured in any suitable manner to the bows 8 and member 5 or other parts of the top frame, and lie close to the under side of the top and virtually serve as a double lining 25 for the greater portion of the under side of the top, following the curve of the top as regards the overhang portions 7. Spacer strips 7^a are mounted between the sheets 3 and 4.

Guide means with which the side edges of the curtains are slidably engaged is provided on each side of the automobile and comprises three post or upright bars 9, 10 and 11 extending from the upper edge of 30 the body 12 to the outer edges of the sheets 3 and 4. Mounted on the opposed edges of these posts are tubular guide members 13 each of which has a vertical slot or opening 14 arranged so that the slots are opposite one another and register with the 35 space between the sheets 3 and 4. The posts and tubes are mortised together as at 15.

The curtains 2 each comprise a relatively heavy but flexible rectangular frame 16 formed of some suitable fabric and which supports a celluloid or other flexible and transparent curtain light 17. At the upper and lower ends of the curtain and attached to the frame portion 16 are wooden or metallic strips 18. Secured to the sides of the curtains are relatively thin flexible leather strips 19 having a series of spaced perforations or openings 20 therein. These strips are adapted to extend thru the slots 14 into the tubes 13 and are attached to slide members 21. The slide members 21 are each in the form of a helical wire coil with the convolutions 22 extending thru the openings or perforations 20. The slide members 21 are of greater diameter than the width of the slots or openings 14 and provide for holding the strips 19, at the edges of the curtains, securely within the tubes 13. To lend rigidity to the slide members, straight wire rods 23 are inserted thru the coils of

the slide members. The slide members 21 each extend from end to end of the curtains and are at all times flexed. When the curtain is drawn upwardly between the sheets 3 and 4 the lower end thereof is flexed by reason of the curvature of the sheets 3 and 4 along their outer edges, as shown in Fig. 8. By this flexing the rods 23 are securely held against falling out of the members 21. The slide members 21 are capable of being moved freely up and down between the guide members and between the sheets 3 and 4. It is not necessary to provide guide rails or members to engage the sides of the curtains when the latter are in 70 up position since the lower portions of the curtains will extend into the guide members 13 and this will prevent any tendency of the curtain to shift or move laterally. The frictional engagement between the slide members 21 and parts of the structure in which they come in contact are such that the curtains will be held against dropping into closed position due to vibration of the automobile. By grasping the tab 24 provided on the lower edges of the curtains, the latter may be raised and lowered as desired. The tab is preferably provided with an opening so as to receive the pin 25 on the upper edge of the car body, whereby 80 the windows may be fastened in down position.

Referring to the frame of the invention shown in Figs. 9, 10, 11 and 12, the top 27 of the automobile is provided on opposite sides with curtains 28 similar to the curtains 2 but adapted to be rolled into concealed position within the top instead of being moved bodily into side position. Upon each side in a longitudinal center line of the top upon the under side thereof is mounted a spring roller 29, similar to the ordinary window shade roller. This roller is supported by brackets 30 depending from the bows of the top and the curtain 28 is attached thereto. Preferably there are two rollers on each side the car and arranged in spaced relation to one another. In this form of the invention it is not necessary to employ guide means beyond the vertical guide portions at the sides of the top. The curtains 28 each comprise heavy flexible fabric frame 32 supporting a celluloid curtain light 33. Attached to the side edges of the frame 32 are strips 34 corresponding to the strips 19. In this connection it will be noted that the slide members, as described in the preferred form of the invention, will be used in connection with the curtain of this form. Detachably secured to the upper edge of the curtain frame 32 is a length of heavy cloth 35 which is attached to the roller 29. This cloth will extend in close proximity to the under side of the curtain and when rolled upon the 90

roller 29 will bring the upper edge of the curtain proper along the upper side of the roller as shown in Fig. 11, the lower edge of said curtain being raised to a point substantially flush to the overhanging portion of the top 27. The meeting edges of the curtain proper and cloth strip 35 are provided with eyelets 36 thru which lacing 37 is inserted so as to detachably secure said parts together. When it is desired to repair or renew either of the parts of the curtain, the disassembling or reassembling may be readily and easily accomplished, by reason of this detachable connection. In this form of the invention, tubular guide members 38 are employed as are the similar members in the preferred form and these guide members will extend upwardly to a point beyond the lower edges of the overlying portions of the top, being curved as at 39 at their upper end so as to follow the curve of the overhanging. When the curtain is pulled down the cloth strip 35 will be extended, as shown in Fig. 9, and when the curtain is raised this strip will be completely concealed upon the roller 29 and the curtain proper will lie close against but exposed beneath the upper part of the top 27, the lower portion of the curtain proper being engaged in the upper curved portions 39 of the guide members 28.

I claim:

The combination with a top and body of an automobile, a flexible side curtain, guide tubes associated with the top and body and having longitudinal slots therein of less width than the inside diameter of the tubes, said tubes being curved upwardly and inwardly at their upper ends to follow the usual curvature of the top, flexible strips secured to and extending along opposite edges of the curtain and slidably mounted within said slots, said strips having spaced perforations therein, helically coiled flexible members slidable in the tubes and having convolutions thereof extended thru the perforations, and a plurality of rods mounted in the tubes which rods extend freely through said coiled flexible members and are curved to correspond to the curve of said tubes.

AUGUST H. PAPE.
